UNITED STATES PATENT OFFICE.

BENEDICT GOODMAN, OF HOLLY, COLORADO.

DESIGN FOR A SWING CHAIR.

Application filed December 18, 1928. Serial No. 29,322. Term of patent 14 years.

To all whom it may concern:

Be it known that I, BENEDICT GOODMAN, a citizen of the United States, residing at Holly, in the county of Prowers and State of Colorado, have invented a new, original, and ornamental Design for a Swing Chair, of which the following is a specification, reference being had to the accompanying drawing, forming part thereof.

I claim:

The ornamental design for a swing chair, as shown.

BENEDICT GOODMAN.
